UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

ASSEMBLED TWIN-WINDOW UNIT.

1,318,297.

Specification of Letters Patent.

Patented Oct. 7, 1919.

Application filed December 12, 1912. Serial No. 736,378.

To all whom it may concern:

Be it known that I, ALLEN E. OSTRANDER, residing at Ridgewood, Bergen county, New Jersey, and being a citizen of the United States, have invented certain new and useful Improvements in Assembled Twin-Window Units, of which the following is a full, clear, and exact description, such as will enable others skilled in the art to which it applies to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

My invention relates to steel passenger car construction and particularly to assemblage elements therefor, and comprehends in its adaptation a unitary window frame for use in passenger car sides.

The object of this invention is to facilitate the assemblage of the usual passenger car construction by the utilization of unitary twin window frame assembled elements arranged in such form as to be applicable to any predetermined post spacing of such construction and to produce a finished window framing immediately upon such application.

In standard car constructions wherein a plate girder construction is employed below the window or belt rail, the wide posts are so spaced as to provide openings for the insertion of twin windows, a narrow post forming a central division thereof, and the roof plate angle unites the tops of said posts. Heretofore the windows were formed by attaching the window frame elements to the posts separately until a window frame was produced. In other constructions where an arched plate was used the arch was shaped to the window contour and was secured to the broad post construction spanning the full window opening, the narrow post being located in the center of and intercepting such space. Such forms of construction necessitated the attaching of the window frame elements in separate parts which were secured together in the position where used but was a considerable advance as far as the car assemblage was concerned.

It will be seen that to produce a completely assembled unit capable of adaptation

to the naked car framing, embracing the post construction and the plate girder and producing a finished twin window framing unit for the exterior or facia of the car body is of great advantage to the art of car building as a commercial article capable of being delivered in quantities and applied to all standard car construction with great facility and despatch.

To more particularly describe this invention a twin window frame is formed as a unit wherein the center supporting portion is in form of a hollow pilaster facia member adapted to embrace the narrow post section of the car construction and wherein the two side portions are in form of hollow semi-pilaster facia members adapted to partially embrace the double or broad post of said car construction, the pilasters being fixed together by suitable means at the top thereof and joined together at the bottom by means of a window sill portion which is adapted to embrace the plate girder of the car side. The top connection of the unit is secured to the inside of the letter plate of the car, or as it is termed, the facia plate.

Referring to the drawings, Figure 1 represents a side elevation of an assembled window frame unit in accordance with this invention.

Fig. 2 represents a horizontal sectional view of the same on the line 2—2 of Fig. 1 looking in the direction of the arrows.

Fig. 3 represents a vertical sectional view on the line 3—3 looking in the direction of the arrows.

Fig. 4 represents a top view of the assembled window frame unit showing one of the small posts in position in dotted lines.

The parts employed to make up the assembled twin window units are as follows: A central hollow pilaster facia member 1 formed with projecting portions 2 and recess portions 3 and hollow semi-pilasters facia members 4 and 5, provided with recesses 6 and 7. These pilasters are adapted to contact with a window sill 8 which is shaped in the usual form of window ledge used in steel car construction and at points where pilasters join the ledge, the ledge is provided with an upstanding flange 9 adapted to fit within the contour of the said pilasters. This upstanding flange as at 10 and 11, where it is in contact with the semi-pilaster, extends beyond the same in a vertical plane

for attachment to a splice plate 12 which is adapted to join the assembled window frame units together. The upper portions of the pilasters are provided with troughs 13 suitably secured thereto and adapted to receive the framing of a fixed window, and the tops of the pilasters are joined together by a Z-shaped bar 14, the flanges of which are cut out where it spans the faces of the 5 pilasters, the lower vertical flange of said Z-shaped bar being attached to the troughs 13. This Z-shaped bar 14 is attached to the pilasters by means of angles 16 suitably disposed therein, and filled plates 15 are interposed between the Z-bar 14 to bring the thickness up to the thickness of the splice plate of the assembled units. In Fig. 4 a 10 method is shown whereby the center pilaster is connected to the narrow post of the car construction as by means of a casting 18 which is secured through the face of the Z-bar and is adapted to contact with the flange of the said post.

The lower portion of the window is preferably made somewhat in the shape of a bulb angle and bent back upon itself in such manner as to form a slot 17 to receive the upper portion of the side wall of the 15 car or side girder plate (not shown). To 20 prevent any strain from forcing the plate girder plate out of the slot thus formed, a filler block 19 is inserted between the lower surface of the window ledge and the upper surface of the upper portion of the slot 25 formed by bending the same into a bulb angle at the window ledge as stated heretofore. In this construction the upper Z-bar is designed to be secured to the inside surface of the letter board or facia plate and 30 the said letter board or facia plate itself projects beyond and over the Z-bar plate forming a shedding surface and at the same time providing a certain clearance within 35 the body of the car above the top of the windows to form a window pocket. The 40 troughs 13 may be omitted from this construction thereby forming a window opening from top to bottom of the assembled 45 element, but as such window would be larger 50 than necessary in ordinary usage it has been found preferable to insert the upper half window or sash and thereby permit of a 55 pocket for receiving the lower window of sufficient height to accommodate practically the entire lower window.

A conveniently formed construction is shown in the drawings and described herein, but the invention is not limited to the shape, size and configuration of the assemblage 60 elements employed as the same must necessarily be changed in the constructional details as may be required by the particular specification of the car to be built.

What I claim is:—

65 1. In metal car construction, an assembled

unit comprising a twin window framing, said framing including semi-pilaster side facia members constructed to embrace car side posts, means permanently joining said members at their upper ends, said means 70 being constructed to be permanently attached to a car side plate, and a window sill permanently securing the lower ends of said members in position.

2. In metal car construction, an assembled 75 twin unit comprising a plurality of pilasters, a plate joining the tops of said pilasters, said plate being constructed to be united with a facia plate of a car, and a window ledge uniting the bottom of said 80 pilasters, said window ledge being constructed to embrace the edge of a plate girder, said window ledge also being recessed to receive car side posts.

3. In metal car construction, an assembled 85 twin window unit comprising a plurality of pilasters, means for permanently joining said pilasters at the upper ends, a window ledge permanently joining the lower ends of said pilasters, said means and said window 90 ledge both being recessed to provide openings whereby said pilasters may be assembled over parts of a metal car frame.

4. In metal car construction, an assembled 95 twin window unit comprising a plurality of pilasters united at the tops thereof, a window ledge adapted to embrace a plate girder, and a filler block inserted within the contour of the window ledge to secure the said window ledge and the said plate 100 girder together.

5. As an article of manufacture, an assembled twin window unit for metal cars, said window unit comprising a plurality of pilasters, a member permanently uniting the 105 tops of said pilasters, a window ledge, up-standing flanges integral with said window ledge and entering within and conforming to the interior contour of said pilasters to secure said pilasters permanently to said window ledge, and means carried by said window ledge to enable same to be secured to a plate girder.

6. In metal car construction, an assembled 115 twin window unit comprising a plurality of pilasters, means for uniting the tops of said pilasters, said means being provided with a portion constructed to be permanently attached to the upper part of a car side, a window ledge permanently secured to the 120 lower ends of said pilasters, said window ledge being provided on its under portion with a longitudinal groove, adapted to engage and embrace the edge of a side plate and a filler block inserted within the contour 125 of said window ledge, substantially as described.

7. As an article of manufacture, an assembled twin window unit for metallic cars comprising a plurality of vertical hollow 130

- 5 pilasters, said pilasters being constructed to inclose and receive car side posts, a Z bar extending between and permanently joining together the upper ends of said 5 pilasters, a window ledge extending between and joining together the lower ends of said pilasters, all of said parts comprising a unitary structure adapted to be assembled upon a suitable car framing to inclose said 10 framing, substantially as set forth.
8. In a metal car construction, a facia plate, an assembled twin window unit comprising a plurality of pilasters, an upper plate uniting the tops of said pilasters and 15 adapted to be secured to the facia plate, a lower side wall member, and a window ledge uniting the bottom of said pilasters and adapted to embrace the upper edge of the lower side wall member.
- 20 9. As an article of manufacture, an assembled twin window unit comprising a plurality of hollow facia members adapted to embrace the side posts of a suitable car frame, a recessed top uniting said facia members, and a window sill provided with members adapted to be secured within the said hollow facia members whereby said window sill joins and supports the lower ends of said 25 members.

Copies of this patent may be obtained for five cents each, by addressing the "Commissioner of Patents, Washington, D. C."

10. In metal car construction, an article 30 of manufacture, comprising an assembled twin window unit having a plurality of pilasters, a longitudinally extending member secured to and uniting the tops of said pilasters, a window ledge secured to and 35 uniting the lower ends of said pilasters, and means on said window ledge to receive the upper edge of a suitable plate girder.

11. As an article of manufacture, an assembled twin window unit for metallic 40 cars comprising a plurality of vertical hollow pilasters, said pilasters being constructed to inclose and receive suitable car side posts, means extending between and permanently joining together the upper ends 45 of said pilasters, and a window ledge extending between and joining together the lower ends of said pilasters, the construction and arrangement of all of said parts comprising a unitary structure adapted to be assembled 50 upon a suitable car framing.

In witness whereof I have hereunto set my hand in the presence of two witnesses.

ALLEN E. OSTRANDER.
